Des. 227,087
Patented June 5, 1973

227,087

SHEET METAL PANEL

Guy Charles Spoo, 18-20 Place Van Meyel,
1040 Brussels, Belgium

Filed July 14, 1971, Ser. No. 163,129

Term of patent 7 years

Int. Cl. D25—01
U.S. Cl. D13—1 J

FIG. 1 is a front perspective view of the invention;
FIG. 2 is a front elevational view of the invention;
FIG. 3 is a side elevational view on the scale of FIG. 1
and taken from the right of FIG. 2; and

FIG. 4 is a rear elevational view showing the side of
the panel opposite the side shown in FIG. 2.

I claim:

The ornamental design for a sheet metal panel, as
shown.
